UNITED STATES PATENT OFFICE.

WILLIAM T. JAMES, OF CHICAGO, ILLINOIS.

CONVEYER.

No. 856,527.

Specification of Letters Patent.

Patented June 11, 1907.

Application filed August 27, 1906. Serial No. 332,149.

To all whom it may concern:

Be it known that I, WILLIAM T. JAMES, a citizen of the United States, residing at Chicago, in the county of Cook and State of Illinois, have invented certain new and useful 5 Improvements in Conveyers, of which the following is a specification.

The invention relates to conveyers and particularly to conveyers for handling coal and similar material, and the invention has for its objects; to provide an improved automatic machine for conveying the coal laterally and elevating it to a position from which it can be delivered by gravity; to provide a 15 horizontal conveying mechanism adapted to operate continuously and effectively without clogging; to provide a flexible elevating conveyer having improved means for dumping the buckets; to provide a flexible elevating conveyer provided with adjusting means whereby the upper end of the conveyer may be moved to various positions without disturbing the driving mechanism; to provide a 20 flexible elevating conveyer provided with an independent top drive movable in the plane of the conveyer for changing the position thereof; to provide a flexible chain conveyer with a plurality of driving means whereby such conveyer may be made a greater length 25 than could otherwise be done, and to provide a flexible elevating conveyer with delivery mechanism which can be adjusted to deliver at any desired height and dump the buckets at such height. One form of the device is 30 shown in the accompanying drawings in which,

Figure 1 is a side elevation showing the assembled mechanism,

Figure 2 is a front elevation of the mechanism shown in Figure 1, but with the driving mechanism at the bottom and top in section,

Figure 3 is a section through the structure of Figure 1 on the line 111—111 of Figure 2,

Figure 4 is a diagrammatic side elevation of 45 a modified form of conveyer having a two-point drive, and

Figure 5 is a front elevation of the conveyer shown in Figure 4.

My device is intended primarily for the 50 handling of coal, especially very fine coal, dust or slack, although the mechanism is obviously capable of handling other materials of similar nature, and consists in the main of the horizontal worm conveying mechanism 55 A, the chain conveyer B for carrying the coal from the trough C to which it is delivered by

the conveyer A, the two lower chain driving means D and E, the upper driving means F with its motor G, all mounted upon the track H for adjustment thereon, and the adjustable chute K into which loaded buckets are adapted to be dumped and from which the coal may be fed by gravity to any desired receptacle or to a conveying means such as a wagon or car.

Describing the device more in detail and referring to the assembled views 1, 2, and 3, the horizontal conveying mechanism A comprises two parallel screws 1—1 (Figure 2) leading from the source of supply, which may 60 be at some distance from the elevating mechanism to the trough C from which the coal is to be carried upwardly by the chain conveyer B. These conveyer screws 1—1 are as shown, placed a slight distance apart and are 65 rotated in opposite directions as indicated by the arrows, thereby feeding along the coal from two sides, which arrangement has been found to be more effective than a single screw in which there is a churning action 70 without a proper amount of forward feed of the coal. The worms or screws 1—1 are mounted upon the shafts 3 carrying bevel gears 4, which bevel gears 4 engage the bevel gears 5 on the drive shaft 6 which is driven 75 by mechanism which will be more fully described hereafter.

The elevating mechanism in its preferred form (Figures 1, 2; and 3,) is triangular in shape and has three driving means or sprockets D, E, and F, above referred to, which sprockets are arranged along the course of the conveyer so as to distribute the strain 80 throughout the chain. The conveyer B itself may be of any preferred construction 85 but preferably comprises the two chain members 7—7 (Figure 2) spaced apart so that the buckets 8 may swing freely between them and are each composed of links 9—9 pivoted together at their ends in the usual 90 way and carrying intermediate such pivot points the rollers 10 which rollers 10 are engaged by the sprockets to drive the conveyer. These rollers also serve to lessen 95 the sliding friction of the horizontal and left hand flight or run of the conveyer by rolling upon the tracks 11 at the sides of the trough C (Figure 2) and upon the members 12 adjacent the left hand vertical run upon which members 12 the trough K is mounted. As 100 before stated the upper driving means F is mounted for transverse movement and this 105

is accomplished by mounting the driving sprocket, motor and intermediate driving gear upon a wheeled truck 13 mounted upon the curved track H. The curve of this track 5 is such that when the truck is moved to various positions thereon the drive chain B will always have the same amount of tension, which fact is of course due to the fact that the sum of the distances from the center of the drive F to the centers of the drive D and sprocket 14 is always the same. The motor G has a belt connection to the pulley 15 and such pulley 15 is keyed to the shaft 16 carrying keyed thereto, a spur gear 17 which 10 meshes with the gear 18 on the drive shaft 19 which shaft 19 carries the driving sprockets F over which the conveyer chains 7 pass. The under side of the track 13 is provided with a clamping means 21 for securing the 15 truck rigidly in position upon the track H. The driving sprockets D are mounted upon the shaft 6 which drive shaft 6 also carries the gear 23 driven from the gear 24 on the shaft 25 carrying the pulley 26, which pulley 20 26 is driven from a motor (not shown) of any preferred form. The driving sprockets E are mounted on a shaft 27 and driven by means of the gear 28 on such shaft, the pinion 29, the pulley 30, and a motor (not 25 shown) belted thereto.

The construction of the buckets 8 and the means for dumping them will now be described reference being had particularly to Figures 1, 2, and 3. As here shown the 30 buckets are of triangular shape and are pivoted near the bottom of one of the sides intermediate the two chains of the conveyer, and the side of the bucket adjacent the pivot point is provided with the tripping member 32 which tripping member is adapted during 35 its upward movement to engage the roller 33 on the chute K thereby tilting the bucket to the position shown in dotted lines in Figure 3, in which position the coal is delivered upon the chute K from which it may be delivered by gravity in a pile upon the floor 34 or into 40 a receptacle or transferring mechanism such as a car or wagon. In order that the bucket may not tilt backward between the chains, 45 the stop members 35 are provided which are located below the point of pivotal support of the buckets and project across the chains and prevent backward movement not only during the vertical movement of the bucket 50 but also while such buckets are moving through the trough C. The chute K is mounted for vertical adjustment by virtue of the sliding engagement of the pins 36 between the members 12 and 12' and the chains 55 60 37—38 by means of which power may be applied to change the position of the chute or by means of which the chute may be counterbalanced with weights. A sliding door 39 is provided in the floor 34 through which 65 door, coal may be dumped and carried to an

elevated position by means of the conveyer, and delivered to any desired point by a chute such as K or some other conveying mechanism.

A modification of the construction is 70 shown in Figures 4 and 5 in which the chain B' is driven at two points by means of the sprockets D' and E' and in which the chute K' is pivoted on the bar 40 which is at an angle to the plane of the chain in order to 75 avoid interference therewith. This conveyer may be arranged to act in conjunction with the other transferring mechanism in substantially the same manner as is done in the preferred form of construction, but the 80 modified construction is not so desirable as the length of the chain and number of buckets must, obviously, be less, and the filling of the buckets is not accomplished as readily and effectively as in the construction of Figure 85 1, for the reason that the buckets do not travel through the long trough C and hence do not have the same opportunity to become filled in their limited period of travel through the coal trough. Furthermore the construction is not so desirable as the space between the chains is less than in the preferred form and the operation of the chute is not as free as in the preferred form in which the triangular space is available for the manipulation of 90 the chute K. The chute K' of the modification may be moved bodily in a vertical direction in the same way as the chute K for the preferred form and the position of the end 95 may be regulated independent of the bodily vertical movement by tilting the chute about its shaft 40.

Having thus described my invention and illustrated its use, what I claim as new and desire to secure by Letters Patent, is the following:

1. In combination, conveying mechanism comprising a trough, a triangular elevating conveyer provided with scoop buckets and having a lower substantially horizontal run in the trough, and means for conveying the material to the end of the trough, in a direction opposite to the movement of the buckets.

2. In combination, conveying mechanism comprising a trough, an elevating conveyer provided with a plurality of runs with scoop buckets and having its lower run in the trough, and means for forcing the material into the end of the trough in a direction opposite to the movement of the buckets.

3. In combination, conveying mechanism comprising a receptacle, an elevating conveyer having a portion thereof in the receptacle, a chute adjustably mounted for movement longitudinally of one of the vertical runs of the conveyer, buckets on the conveyer, and automatic means for dumping the buckets into the chute.

4. In combination, conveying mechanism

comprising a receptacle, an elevating conveyer having a portion thereof in the receptacle, a chute adjustably mounted for movement longitudinally of one of the vertical runs of the conveyer, buckets pivoted to the conveyer and having projections whereby they may be tilted, and means on the chute for engaging the projections to dump the buckets into the chute.

10. 5. In combination in conveyer mechanism, opposing flexible bucket supports, buckets pivoted therebetween at the sides, tilting projections on such sides and a longitudinally adjustable projection adjacent one of the runs of the flexible supports for engaging the tilting projections for dumping the buckets.

15. 6. In combination in conveyer mechanism, opposing flexible bucket supports, buckets pivoted therebetween at the sides, tilting projections on such sides and a longitudinally adjustable chute provided with means adjacent one of the runs of the flexible supports for engaging the tilting projections for dumping the buckets.

20. 7. In combination in conveyer mechanism, opposing sprocket chains, buckets pivoted therebetween at the sides, tilting projections on the pivoted sides, stops on the buckets for engaging the chains to prevent

25. backward tilting of the buckets, and means adjacent one of the vertical runs for engaging the tilting projections to dump the buckets.

30. 8. In combination in conveyer mechanism, a chain bucket carrier in substantially

the form of a triangle, buckets thereon, and 35 three sets of driving means arranged along the course of the carrier.

9. In combination in conveying mechanism, a receptacle, a triangular elevating conveyer provided with buckets and having its 40 lower run in the receptacle, and a plurality of driving means for the lower run.

10. In combination in conveying mechanism, a receptacle, a triangular elevating conveyer provided with buckets and having its 45 lower run in the receptacle, driving means at the upper apex of the triangle, and a plurality of driving means for the lower run.

11. In combination in conveying mechanism, an endless chain conveyer provided 50 with buckets, a sprocket at the upper end of the conveyer and a curved track carrying the sprocket whereby it may be adjusted laterally in the plane of the conveyer.

12. In combination in conveying mechanism, an endless triangular chain conveyer provided with buckets, a curved track at the top of the conveyer, and a sprocket drive and motor mounted for movement along the track.

In testimony whereof, I have hereunto signed my name in the presence of the two subscribed witnesses.

WILLIAM T. JAMES.
